UNITED STATES PATENT OFFICE.

THEODORE ABTMAYER, OF WILKINSBURG, PENNSYLVANIA, ASSIGNOR TO WESTINGHOUSE ELECTRIC AND MANUFACTURING COMPANY, A CORPORATION OF PENNSYLVANIA.

PERCOLATOR.

1,124,683.

Specification of Letters Patent.

Patented Jan. 12, 1915.

Application filed June 5, 1913. Serial No. 771,861.

To all whom it may concern:

Be it known that I, THEODORE ABTMAYER, a citizen of the United States, and a resident of Wilkinsburg, in the county of Allegheny and State of Pennsylvania, have invented a new and useful Improvement in Percolators, of which the following is a specification.

My invention relates to electric heating apparatus and it has special reference to percolating devices of the type adapted for immersion in liquid.

One object of my invention is to provide a device of the above-indicated character which shall be simple and inexpensive in construction, convenient to assemble and reliable and particularly effective in operation.

Another object of my invention is to provide a percolator which, by reason of its peculiar structure, shall be especially economical in operation and maintenance.

In the prior art, percolators have embodied heating members that utilize either an inner or an outer liquid-heating surface exclusively, with the result of loss of efficiency during operation and short life of the heating element by reason of overheating.

According to my present invention, I employ a heating member that is provided with both inner and outer liquid-heating surfaces, thereby securing rapid and forceful operation at a relatively low current consumption and, since the possibility of overheating the element is precluded, by reason of the water jacket on three sides, a relatively long life of the heating element is insured.

In the accompanying drawing, Figure 1 is a view of a portion of a suitable vessel that embodies a percolating device shown in longitudinal section and constructed in accordance with my invention, and Fig. 2 is a sectional view, looking upward, with parts broken away, on the line II-II of Fig. 1.

Referring to the drawing, a percolating device 1 is secured preferably to a false bottom 2 of a suitable liquid-containing vessel 3, and the necessary electrical terminal members 4 for the device are disposed in the vessel beneath the false bottom 2 or in any convenient manner. It is understood that any other suitable means of assembly and support may be employed.

The percolating device 1 comprises an

electric heating element 5, a suitably heat-insulated annular incasing member 6 and a fountain tube 7.

The heating element 5 preferably comprises an electrical conductor 8 that is helically wound on an insulating hollow spool 9 having external end flanges 10, by which construction I avoid the use of any special insulating material for inclosing the conductor 8, inasmuch as the annular air-space 69 that is formed provides the necessary electrical insulation. The ends of the conductor 8 are preferably disposed in suitable openings 11 in the spool 9 and are connected to the terminal members 4 in any appropriate 65 70 fashion.

The member 6 comprises an inner cylindrical tube 12, that is closed at the bottom, and an outer cylindrical shell 13 that are respectively adapted to engage the central 75 opening and the upper end flange 10 of the spool 9, thus providing surfaces that are adapted for liquid-heating purposes both within and without the heating element. The shell 13 has a lower expanded portion 80 upon which is adapted to rest a cylindrical shell 14 that has a contracted upper end to engage the fountain tube 7 and is disposed around the shell 13 to form a suitable liquid-containing chamber 15. An outer shell 16 85 surrounds the shell 14 and is suitably spaced therefrom for heat-insulating purposes, the corresponding ends of the shells being suitably united. The lower ends of the shells 14 and 16 may be provided with outwardly disposed lips 17, or other suitable means, for admitting liquid to the chamber 15.

The fountain tube 7, that may be of any convenient form, extends through the upper end of the shell 14 and has its lower end 95 preferably adjacent to the bottom wall of the central tube 12. A plurality of openings 18 are preferably provided in the fountain tube 7 just above the tube 12.

It will be observed that the fountain tube 7 and the two shells 14 and 16 form a unitary member that is adapted for ready removal and replacement.

The principle of operation of my device is deemed sufficiently well known to obviate 105 the necessity of any extended description. One path of the percolating liquid may be traced as follows: Liquid is admitted through the lips 17 to the chamber 15 and passes upwardly and then downwardly into 110

the central tube 12 and next through the fountain tube 7, again to the main body of the vessel 3. Another path leads directly from the chamber 15 through the openings 5 18 into the fountain tube 7. It will thus be seen that a relatively long heating path for the liquid is provided, which results in rapid and forceful circulation. Other advantages of the foregoing construction have herein- 10 before been pointed out.

I do not wish to be restricted to the specific structural details herein set forth, but desire that only such limitations shall be imposed as are indicated in the appended 15 claims.

I claim as my invention:

1. In a percolating element, the combination with a fountain tube, of a heating member and means for utilizing an inner and an 20 outer heating surface thereof.

2. In a percolating element, the combination with a fountain tube, of a heating member, and liquid-containing means for utilizing an inner and an outer heating surface 25 thereof.

3. In a percolating element, the combination with a fountain tube, of a heating member, and liquid-containing chambers disposed both within and without said heating 30 member and in good thermal contact therewith.

4. In a percolating element, the combination with a heating member, of an outer annular chamber and an inner chamber severally in good thermal contact with said 35 member, and a fountain tube disposed within in said inner chamber.

5. In a percolating element, the combination with a longitudinally-disposed heating 40 member, of an outer annular chamber and an inner chamber severally longitudinally disposed and in good thermal contact with said member, a fountain tube disposed with-

in said inner chamber, and means for admitting liquid to said chambers. 45

6. A heater adapted for immersion in a liquid-containing vessel and comprising a heating member, an outer annular chamber and an inner chamber severally in good thermal contact with said member, and a 50 fountain tube disposed within said inner chamber.

7. An electrically heated percolator comprising an annular heating element, a fountain tube disposed within the said element, 55 and a heat-insulating annular member surrounding the said heating element and spaced therefrom.

8. An electrically heated percolator comprising an annular heating element, a fountain tube disposed within the said element, and an annular member surrounding the said heating element, spaced therefrom, and having a reduced end that is secured to the 60 said fountain tube. 65

9. An electrically heated percolator comprising an annular heating element provided with an inner and outer casing, the outer casing having an outwardly enlarged portion, a fountain tube disposed within the 70 said heating element, an annular member surrounding the said heating element, spaced therefrom, and having a reduced end that is secured to the said fountain tube, the other end resting upon the enlarged portion 75 of the casing, and means for permitting the entrance of liquid between the said annular member and the heating element.

In testimony whereof, I have hereunto subscribed my name this 28th day of May 80 1913.

THEODORE ABTMEYER.
